UNITED STATES PATENT OFFICE.

ALLEN CLYMER AUSTIN, OF SYRACUSE, NEW YORK.

PRESSING-MACHINE.

1,354,232.

Specification of Letters Patent. Patented Sept. 28, 1920.

Application filed September 9, 1918. Serial No. 119,197.

To all whom it may concern:

Be it known that I, ALLEN CLYMER AUSTIN, a citizen of the United States, and a resident of Syracuse, in the county of Onondaga and State of New York, have invented a certain new and useful Pressing-Machine, of which the following is a specification.

This invention relates to pressing machines such as that of my pending application, Sr. No. 54,149, filed Oct. 5, 1918, and has for its object a particularly simple, efficient and economical frame construction for pressing machines; and the invention consists in the novel features, and in the combinations and constructions hereinafter set forth and claimed.

In describing this invention, reference is had to the accompanying drawings in which like characters designate corresponding parts in all the views.

Figure 1 is a side elevation of a pressing machine embodying my invention.

Fig. 2 is a front elevation of the frame, partly broken away.

Fig. 3 is a side elevation of the frame, the parts thereof being separated.

Fig. 4 is an inverted plan view of the table.

Fig. 5 is an edge view of the table looking upwardly in Fig. 4.

Fig. 6 is a plan view of the upper face of the front legs.

Fig. 7 is a fragmentary view of the rear leg illustrating the bearing face thereon.

This pressing machine comprises a frame, a stationary pressing element or buck supported by the frame, a movable pressing element or head, a movable support for the pressing head, and means for operating the movable support.

The frame, as here illustrated, comprises a table, front and rear legs supporting the table, the table and the legs being provided with complementary bearing faces which incline downwardly and inwardly and preferably have high or raised portions which engage when the parts are assembled, and fastening members extending through the bearing faces. These inclined bearing faces insure snug and rigid engagement of the parts and the high or raised portions thereof eliminate the necessity of accurate machining, as it is not necessary that the faces be fitted throughout their entire area, but only at their high or raised points which can be

made to come together without machining. In this form of my invention there are two front legs constructed as a single unit, and a single rear leg located midway between the sides of the frame.

60

1 designates the table; 2 the front legs, and 3 the single rear leg, the table being here shown as a plate having bearing faces 5 6. The bearing faces 5 are located at the front corners of the table, on the under side 65 thereof, and are inclined downwardly and rearwardly or inwardly toward the center of the frame, out of a horizontal plane, and have high or raised portions 7 which project farther below the table than the remaining 70 parts of said bearing faces. As here illustrated the raised portions 7 extend along the margins of the faces 5 so that the central portions of the faces 5 are depressed.

The bearing face 6 is located on a web 8 75 depending from the rear side of the table and is inclined downwardly and slightly inwardly or forwardly out of a vertical plane, and is provided with raised or high portions 9 at its opposite ends. Reinforcing webs 10 80 extend from the opposite ends of the web 8 on which the bearing surface 6 is provided, to the bearing faces 5. The table 1 is also formed with a rearwardly extending horizontal flange or shoulder 11 located along 85 the upper edge of the face 6.

The front legs 2 are cast as a unit in one piece and are connected at their upper ends by a web 12 and at their lower ends by a brace 13 which curves or convexes inwardly 90 toward the rear side of the machine.

The front legs 2 are provided at their upper ends with bearing surfaces 14 which are complementary to the bearing surfaces 5 and inclined out of a horizontal plane, the 95 planes of these faces 14 being arranged at a right angle to a plane containing the axes of the legs 2 which axes preferably are not perpendicular but diverge or spread toward the lower ends of the legs.

100

The rear leg 3 is a pillar in the form of a channel in cross section and is arranged with its channel facing rearwardly. Said leg is provided with an extension at its upper end, constituting a bracket 15 which carries a bearing 16 at its upper end, the bearing being located substantially in a vertical plane intersecting the leg 3 throughout its length. The rear leg is provided with a bearing face 17 inclined out of a vertical 110

plane and arranged in position to coact with the bearing face 6 of the table, the bearing faces 6 and 17 each having high or raised portions which engage when the parts are assembled. The rear leg 3 is also formed with a seat or ledge 18 having substantially vertical and horizontal faces for engaging the edge and under faces of the flange or shoulder 11 of the table 1. The flange 11 and ledge 18 constitute interlocking shoulders arranged to relieve the bearing faces 6 and 17 from strain of supporting the table and also to relieve the bolts passing through said faces 6 and 17 from shearing strain.

15 Fastening members as bolts 19, 20 are passed through the central depressed portions of the bearing faces 5 and through the bearing faces 14 of the front legs, one of the bolts as 19 of each set extending through a 20 slot 21 formed in the leg and opening through the rear edge of the companion bearing face 14.

One of the bolt holes 22 through one of the bearing faces 5 of the table is a slot. 25 The bolt which passes through this slot 22 also serves to secure to the table, a bracket which is mounted on the table and supports the lower buck. This bracket is secured at three points by bolts passing through slots 30 23 in the table, the slots 22, 23 permitting a limited adjusting movement of the bracket.

Fastening members as bolts 24 are passed through the high points of the bearing faces 6 and 17. The front and rear legs are 35 connected by detachable braces 26 bolted at their front ends at 27 to the legs 2, respectively, and at their rear ends 28 to the rear leg 3, the rear leg being provided with laterally extending webs 29 to which the braces 40 26 are bolted.

The rear leg is also provided with a slot 30 at its lower end and with forwardly extending flanges 31 on opposite sides of the slot to which the operating lever to be 45 scribed is pivoted.

32 designates the lower pressing element or buck.

33 is the upper pressing element or head. 34 is the bracket previously referred to 50 which supports the lower buck and which in turn is mounted upon the table 1 and secured thereto by the bolts passing through the slots 22, 23.

35 is the support for the pressing head 33, 55 this support being a lever mounted between its ends on a shaft 36 arranged in the bearing 16, the front arm of the lever carrying the pressing head 33 and the rear arm of the lever being connected to the operating 60 means.

The operating means includes a foot lever 37 pivoted at 38 to the flanges 31 at the lower end of the rear leg 3, an arm 39 rigid with the lever 37 and extending upwardly 65 through the slot 30 and forming one link

of a toggle, and a toggle link 40 pivoted at 41 to the upper end of the arm 39 and at 42 to the rear end of the support lever 35. The downward movement of the lever 37 carries the joint 41 of the toggle toward the dead center line thereof, and such movement is against the action of a spring 43.

An adjustable foot piece 44 is mounted on the front end of the lever 37, said foot piece being movable into the space in front of an 75 intermediate part of the brace 13 connecting the front legs 2.

The toggle link 40 includes end pieces or bearings 45, 46 mounted on the pivots 41, 42 respectively and a rod 47 threading into 80 the upper bearing member 46, the rod being held in position by a lock nut 48 and being operable or rotatable by a hand wheel 49, the hub of which bears against the lower end piece 45, the hand wheel being fixed at 85 50 to the rod.

Obviously, by turning the wheel 49, upon loosening of the nut 48, the length of the link 40 can be increased or decreased. Instead of the lock nut 48, the rod 47 may be 90 locked by a spring pawl 48a coacting with ratchet teeth on the periphery of the wheel 49.

In order to limit the movement of the toggle joint 41 relative to the dead center line 95 of the toggle, the end piece 45 is provided with front and rear arms 51, 52 extending downwardly in the front and in the rear of the upper end of the toggle link 39 and carrying adjustable stops as screws 53, 54 100 which engage at 55 and 56 respectively with the toggle link 39.

Obviously, the stop 54 will limit the movement of the toggle joint into and beyond a straight line and the stop 53 will limit the 105 breaking movement of the toggle joint out of a straight line.

The operating means also includes a weight 57 mounted on the pivot 42 and having forwardly extending arms 58 pressing 110 upwardly on the rear arm of the supporting lever 35 for the movable pressing head 33.

The steam system of this machine is the same as in my pending application referred 115 to and includes the flexible coupling 59.

This machine is advantageous in that its parts can be assembled without accurately machining faces which engage.

It is further advantageous in that owing 120 to the arrangement of its rear leg, the stress due to the pressing operation of the movable pressing head, extends vertically of the central rear leg or pillar 3, and hence the operation of the machine does not tend 125 to tear apart or loosen any of the parts in the machine.

What I claim is:—

1. A machine frame comprising a table, legs supporting the table and being detach- 130

ably secured thereto, the table being formed with bearing faces inclining inwardly and downwardly and the legs being formed with complementary bearing faces, substantially as 5 and for the purpose set forth.

2. A machine frame comprising a table, legs supporting the table and being detachably secured thereto, the table being formed with bearing faces inclining inwardly and 10 downwardly and the legs being formed with complementary bearing faces, some of the bearing faces being provided with raised portions for engaging the bearing faces coacting therewith, and fastening members 15 for securing the table and the legs together, substantially as and for the purpose described.

3. A frame for pressing machines comprising a table, a rear leg, and a unit comprising two front legs, the table being provided with bearing faces inclined out of a horizontal plane on the under side thereof and near the front corners of the table, and with a bearing face on the rear edge thereof 25 of inclined inwardly and downwardly out of a vertical plane, and the front and rear legs being provided with complementary bearing faces, substantially as and for the purpose set forth.

4. A frame for pressing machines comprising a table, a rear leg, and a unit comprising two front legs, the table being provided with bearing faces inclined out of a horizontal plane on the under side thereof 35 and near the front corners of the table, and with a bearing face on the rear edge thereof inclined inwardly and downwardly out of a vertical plane, the table and the rear leg being formed with interlocking shoulders 40 arranged to relieve the bearing faces on the rear edge of the table from strain, and the front and rear legs being provided with complementary bearing faces, substantially as and for the purpose set forth.

5. A frame for pressing machines comprising a table, a rear leg, and a unit comprising two front legs, the table being provided with bearing faces inclined out of a horizontal plane on the under side thereof 50 and near the front corners of the table, and with a bearing face on the rear edge thereof inclined inwardly and downwardly out of a vertical plane, the table being formed with a horizontally and rearwardly extending flange at the upper edge of the bearing face at the rear edge of the table and the rear leg being formed with a seat for said flange and the front and rear legs being provided with complementary bearing faces, substantially as and for the purpose set forth.

6. A machine frame comprising a table, a rear leg and a unit comprising two front legs, the table being provided with bearing faces inclined out of a horizontal plane on 55 the under side thereof and near the front

corners of the table, and with a bearing face on the rear edge thereof inclined inwardly and downwardly out of a vertical plane, the front and rear legs being provided with complementary bearing faces, and fastening 70 members extending through the coacting bearing faces of the legs and the table, substantially as and for the purpose described.

7. A machine frame comprising a table, a rear leg and a unit comprising two front 75 legs, the table being provided with bearing faces inclined out of a horizontal plane on the under side thereof and near the front corners of the table, and with a bearing face on the rear edge thereof inclined inwardly 80 and downwardly out of a vertical plane, the front and rear legs being provided with complementary bearing faces, and fastening members extending through the coacting bearing faces of the legs and the table, the 85 rear leg and the table having interlocking shoulders arranged to relieve from shearing strain the fastening members extending through the bearing faces on the rear leg and the rear edge of the table. 90

8. A machine frame comprising a table, a rear leg and a unit comprising two front legs, the table being provided with bearing faces inclined out of a horizontal plane on the under side thereof and near the front 95 corners of the table, and with a bearing face on the rear edge thereof inclined inwardly and downwardly out of a vertical plane, and the front and rear legs being provided with complementary bearing faces, some of the 100 bearing faces being formed with high or raised portions engaging the coacting faces, substantially as and for the purpose specified.

9. A frame for pressing machines comprising a table, a rear leg, a unit comprising two front legs, the table being provided with bearing faces inclined out of a horizontal plane on the under side thereof and near the front corners of the table, and with a bearing face on the rear edge thereof inclined inwardly and downwardly out of a vertical plane, and the front and rear legs being provided with complementary bearing faces, some of the bearing faces being 110 formed with high or raised portions engaging the coacting faces, and fastening members extending through the bearing faces, the rear leg and the table being formed with interlocking shoulders arranged to relieve from strain the fastening 115 members passing through the faces on the rear edge of the table, substantially as and for the purpose set forth. 120

10. A pressing machine comprising a frame including a single rear leg, a table supported at its rear edge by the rear leg, and front legs supporting the front edge of the table, a lower pressing head supported on the table, the single rear leg having an 125 130

- upwardly extending bracket, an upper pressing head, a lever pivoted to the upper end of the bracket and supporting the upper pressing head on the front arm thereof, an operating lever pivoted to the lower end of the rear leg, and power transmitting means between the operating lever and the rear arm of the former lever, substantially as and for the purpose described.
- 10 11. A pressing machine comprising a frame, a table, and legs supporting the table, including a single rear leg located midway between the sides of the table, the rear leg being in the form of a channel in cross section arranged with the channel facing rearwardly, substantially as and for the purpose set forth.
12. A pressing machine comprising a frame, a table, and legs supporting the table including a single rear leg located midway between the sides of the table, the rear leg being in the form of a channel in cross section arranged with the channel opening rearwardly, the leg being formed with a bearing face on its front side and the table having a complementary bearing face coacting with the bearing face of the leg, substantially as and for the purpose specified.
13. A pressing machine comprising a frame including a table, a single rear leg 30 and a unit including a pair of front legs, an integral web connecting the upper ends of the front legs and an integral brace connecting the lower ends thereof, the single rear leg being located midway between the side edges of the table and being in the form of a channel in cross section and arranged with the channel facing rearwardly, the rear leg having an extension carrying a bearing at its upper end, the table being provided with a set of bearing faces, and the legs being provided with a set of bearing faces coacting with the former faces, one set of bearing faces being provided with high or raised portions, and fastening members 45 extending through the bearing faces, substantially as and for the purpose set forth.
- In testimony whereof, I have hereunto signed my name at Syracuse, in the county of Onondaga, and State of New York, this 22nd day of May, 1916.
- ALLEN CLYMER AUSTIN.
